UNITED STATES PATENT OFFICE.

ERNEST DIGBY HOPCROFT, OF KIDDERMINSTER, ENGLAND.

PROCESS OF REMOVING SCALE FROM BOILERS.

SPECIFICATION forming part of Letters Patent No. 661,873, dated November 13, 1900.

Application filed April 27, 1899. Serial No. 714,768. (No specimens.)

To all whom it may concern:

Be it known that I, ERNEST DIGBY HOPCROFT, boiler inspector, a subject of the Queen of Great Britain, and a resident of Farfield, 5 Kidderminster, in the county of Worcester, England, have invented a certain new and useful Improvement in a new or Improved Process of Removing Scale from Boilers, (for which I have applied for a patent in Great Britain, No. 20,728, dated October 1, A. D. 1898,) of which the following is a specification.

My invention has for its object a new or improved process for removing scale from boilers, which is equally applicable to all 15 kinds of boilers, whether tubular or otherwise, as well as to steam condensers, economizers, and other similar apparatus, by which the scale is readily removed from those parts of the interior surface of the boiler upon which 20 it has accumulated, including the interior of tubes and other parts hitherto inaccessible, and this is effected without recourse to the expensive processes now in use and without removing the boiler from its bed or position, 25 while at the same time the use of antiscale solutions is thereby obviated.

In order that my invention may be clearly understood and more easily carried into practice, I have appended hereunto two sheets of 30 drawings upon which I have illustrated the application of my process to an ordinary vertical boiler, and from which its application to other forms of boiler and other apparatus will readily be understood.

35 Figure 1 is a vertical section through a boiler and through the apparatus for removing the scale therefrom. Fig. 2 is a plan of a similar boiler, but showing a modification in the apparatus suitable for use when dealing 40 with certain classes of scale.

In carrying my invention into effect I first empty the boiler of all superfluous moisture and afterward lower the temperature of the interior to below freezing. I generally, however, 45 find it necessary to lower the temperature to below 25° Fahrenheit, the variations of the requirement being rendered necessary by the different character and thickness of the various scales as well as by the quantity 50 of surface to be dealt with, while at the same time it is important that as far as possible an even temperature shall be maintained

over the whole area of the boiler required to be treated.

I believe the action of removing the scale 55 which takes place to be as follows: During the formation of the scale the whole of the metal in the boiler is in a state of expansion, with the result that upon cooling down to a natural temperature the metal is contracted 60 while the scale remains in its original condition; but upon lowering the temperature within the boiler to, say, 15° or 25° Fahrenheit the metal of the boiler is further contracted, and as the scale is not affected by 65 the lowering of the temperature in the same way or to the same extent as the metal the scale is broken up and separated from the metal. During the process of contraction of the metal I believe that the natural moisture 70 contained in most classes of scale is expanded by the lower temperature which I provide, and that therefore the extra contraction of the metal in combination with the expansion of the scale, which combination is effected 75 by my improved process, is responsible for the easy removal of the scale from the surface of the metal.

I will now proceed with reference to Fig. 1 to describe one method of obtaining and 80 evenly distributing the temperature required in the ordinary vertical boiler illustrated by A, in connection with which the compressor B, condenser C, and cooling-chamber D form part. The compressor B may be of any well-known form, such as here illustrated, having plunger b^3 and cylinder b^4 , with inlet-valve b^1 and outlet-valve b^2 , the latter of which is connected with the condenser-coil C at c' . This coil C is in turn connected with the pipe 85 e' in cooling-chamber D, and from thence a series of circulating-coils E pass to the pipe e^2 , which is connected with the inlet-valve b' of the compressor. The condenser-tank c^2 is supplied with water at F, which passes off 90 again at F' , and a centrifugal pump H is provided in the air-cooling chamber D for raising the chlorid of calcium J into troughs h' , which are placed over each circulating-coil E and perforated for the chlorid of calcium 95 to drip onto the members of the coil, and thereby prevent the accumulation of frost on the pipes. The air-cooling chamber 100 D is provided with the air-propeller K, the

outlet k' of which is connected to the boiler through the hand-doors a' and a^2 by the flexible pipes k^2 and k^3 . The compressor B is provided with stop-valves P and R and is 5 driven by any suitable means, such as the driving-band b^{12} , as also the centrifugal pump H and air-propeller K, which are respectively driven by the bands h^2 and h^4 . The action of the apparatus for the lowering of the temperature 10 in the boiler A is as follows: The compressor, condenser, and cooling-chamber coils being charged with NH_3 or other suitable gases the circulation, as indicated by the arrows, is set up by the action of the compressor, 15 with the consequent cooling of the air in the chamber D. The cold air is then drawn from the chamber D and propelled into the boiler A at any convenient point or points, such as the hand-holes a' and a^2 , but in such 20 a manner as to get the distribution of the temperature over that portion of the boiler covered with scale as even as possible, the air being then allowed to escape at or near the top from any convenient point, such as 25 the manhole a^5 , or in cases where the temperature is lower than the exterior atmosphere it may be conveyed back to the cooling-chamber P by any suitable flexible pipe S.

In cases where the scale is hard and particularly free from moisture and where copper does not form part of the boiler or apparatus I may omit the cooling-chamber D and connect the one end of the condensing-coil C direct with the lower part of the boiler A, as 30 shown at c^3 , Fig. 2, in which case the boiler is connected near the top with the compressor B by pipe p^2 , by which the NH_3 or other gases may be expanded into the boiler, in which case I first create a vacuum in the boiler of, say, 35 from thirty to thirty-three inches. To effect this, I open valve P' and draw spindle of valve T for discharge of air, all the other valves being closed, thus by means of the compressor creating a vacuum in the boiler, after which 40 I close discharge-valve T and open valve R' and regulate the quantity of gas entering the boiler by the regulating-valve Y. The valve W and cylinder X containing gas are for 45 charging the machine.

50 In cases where it is desirable to first test the boiler by air-pressure the valves R' and P' are closed, valve V is open for the admission of the air, and valves T and U are open, by which the air is conveyed to boiler by 55 pipe p^2 .

I may obtain the required reduction in the temperature by liquefied air, which in the

case of boilers of the Lancashire or Cornish type may be effected by the introduction of open vessels, cylinders, or drums containing 60 the liquefied air, or in cases of small boilers I may introduce the same into the boiler at various points by means of the hand-holes or valve connections, and in most cases I prefer to work with a closed boiler under pressure 65 of the gas formed by the pressure of the liquefied air.

In some cases where motive power is difficult and expensive to obtain for the working of the refrigerating apparatus I may effect 70 the required reduction of temperature by the use of chlorids or freezing mixtures applied in a similar manner to that described with reference to liquefied air.

In classes of scale having fifteen or more 75 per cent. of salt I find it necessary to coat the scale with a solution of sal-ammoniac.

The form or shape of my refrigerating apparatus and the particular mode of application are immaterial to the effect and may be 80 adapted to the local circumstances and situation so long as they are capable of producing and evenly distributing the required change of temperature, as hereinbefore set forth.

For purposes of ready transport I prefer to 85 build up my compressor, condenser, and cooling-chamber with a motor complete upon a suitable carriage, by which it may be readily conveyed to the various boilers requiring to be scaled.

Having now described my invention, what I claim as new, and desire to secure by Letters Patent, is—

1. The process for removing scale from boilers which consists in applying to the boiler a 95 temperature below the freezing-point artificially produced and sufficient to effect the separation of the scale from the boiler.

2. A process for removing the scale from boilers, which consists of artificially lowering 100 the temperature of the interior of the boiler from five to twenty degrees below freezing-point, to cause a contraction of the metal of the boiler, and an expansion of the scale to effect a separation of the scale from the boiler, 105 substantially as specified.

In testimony whereof I have hereunto set my hand in the presence of two subscribing witnesses.

ERNEST DIGBY HOPCROFT.
